UNITED STATES PATENT OFFICE.

CHARLES J. AHRENFELDT, OF NEW YORK, N. Y.

DESIGN FOR A PLATE OR SIMILAR ARTICLE.

SPECIFICATION forming part of Design No. 31,708, dated October 24, 1899.

Application filed March 3, 1899. Serial No. 707,676. Term of patent 7 years.

To all whom it may concern:

Be it known that I, CHARLES J. AHRENFELDT, a citizen of the United States, residing at the city of New York, county of New York, 5 and State of New York, have invented and produced a new and original Design for a Plate or Similar Article, of which the following is a specification, reference being had to the accompanying drawings, forming a part hereof, o and like letters referring to like parts in each figure of the same.

In the said drawings, Figure 1 is a plan view of a plate with my design placed thereon. Fig. 2 is a medial vertical section of the same.

5 In the design upon the plate, A consists of a wreath of leaves A' quartered by roses A² and having stems A³, bearing leaves extending from its lower part at either side.

B is composed of two leaf-bearing stems B', crossing each other and forming an X, and a 20 fillet or ribbon B², intertwined with the leaves thereof.

The two ornaments A and B are alternated around the inside of the wreath or circle of leaves C, the whole forming a floral border. 25

This design may be applied to articles other than plates.

What I claim is—

The design for a plate or similar article substantially as herein shewn and described. 30

Signed at the city of New York, in the State of New York, this 10th day of February, 1899.

CHARLES J. AHRENFELDT.
